UNITED STATES PATENT OFFICE.

JACOB N. MCINTIRE, OF NEW YORK, N. Y., ASSIGNOR TO THE BRUNSWICK-BALKE-COLLENDER COMPANY OF NEW YORK, OF NEW YORK, N. Y., A CORPORATION OF NEW YORK.

BOWLING-ALLEY BALL-RETURNWAY.

1,144,145.

Specification of Letters Patent. Patented June 22, 1915.

Application filed September 18, 1911. Serial No. 650,068.

To all whom it may concern:

Be it known that I, JACOB N. MCINTIRE, a citizen of the United States, residing in the city of New York, in the county of New York and State of New York, (whose post-office address is No. 1409 Prospect avenue, New York city, New York,) have invented a new and useful Improvement in Bowling-Alley Ball-Returnways, of which the following is a specification, reference being had to the accompanying drawing, forming a part thereof.

My invention relates to ball returnways for bowling alleys, and especially to that kind which homes the balls, initially, onto the rearmost end of the ball-rack or "terminal" that is located at the player's end of the alley.

This genus of ball returnway, which is now extensively in use, and has come to be known to the manufacturers and users of bowling alleys, as the "loop-the-loop" return, was first disclosed in and was made the subject matter of U. S. Letters Patent No. 630,728 granted Aug. 8th, 1898. As set forth in said patent, the construction of this genus of return is such that, by means of a rapidly descending pit-end portion of the ball-track, and a long low-down horizontal portion running thence to the player's end and there into a rearwardly and upwardly curved portion called the "loop," the balls put on at the upper end of the "sweep" roll rapidly down on it, pass thence onto the long low-down portion of the ball-track, and roll thereon to the player's end of the alley with sufficient speed to travel up in the "loop," and pass thence onto the rearmost end of the "terminal," for reuse by the player. In the (extensive) use of this patented genus of returnway, it has been found that, while constructed as heretofore (under said patent), the larger series of the balls with which a bowling alley is usually equipped, and used for playing ten-pins, roll home onto the "terminal" and not too fast, so as to injuriously "smash-up" together as they congregate on said "terminal," and so as to render it dangerous or inconvenient for a player to get hold of a ball as it emerges from the "loop" onto the "terminal," but the smaller balls, especially those of a diameter less than six

inches, will not get home onto the "terminal." In the ball equipment of a modern "regulation" bowling alley those balls used for playing ten-pins range in size from 27 to 26, and 25 inches in circumference; the 27 inch ball being the "regulation" ball and used mostly by the professional and expert bowlers. And the respective weights of these balls are, approximately as follows: the 27 inch, 15 lbs. $\frac{1}{4}$ oz., the 26 inch 13 lbs. 12 oz., and the 25 inch 11 lbs., 12 oz. And, in practice on the "loop-the-loop" return, as always heretofore made, these balls will roll home onto the "terminal" satisfactorily. But with this construction the smaller balls, which weigh respectively as follows: the 4 inch diameter 1 lb., $10\frac{1}{2}$ oz., the $4\frac{1}{2}$ inch diameter 2 lbs. $4\frac{1}{4}$ ozs., and the 5 inch diameter 3 lbs. $3\frac{3}{4}$ ozs., will not ascend within the "loop" and be discharged therefrom properly onto the "terminal."

It has been found that, in practice the smallest ball and the next smaller size will rarely roll up and onto the "terminal," and as when not getting onto the ball-rack, such balls fall or fly off onto the floor, and are liable to seriously injure the foot of a player, such sized balls cannot be used on an alley provided with the present construction of "loop-the-loop" return. And as these smaller balls are always used (and none of the larger series) for playing the games of "duck pins" and "candle pins" it follows that alleys equipped with the "loop-the-loop" returns adapted to properly home ten-pin balls cannot be used for the other named games.

My invention has for its object to provide for use a ball returnway of the "loop-the-loop" genus (which is far superior to all other styles in the particular of landing the homed balls onto the rearmost end of the "terminal") so constructed that both the larger and the smaller series of balls—(in fact, balls of all sizes) will be landed properly on the "terminal," whereby it is made possible to use the alley for the playing of ten-pins—with the big balls—and also the playing of "duck-pins" and "candle-pins" with the small balls. And to this end and object my invention may be said to consist essentially, in a returnway of the "loop-the-loop" genus, constructed

so that while all the smaller balls will travel homeward and onto the "terminal" with certainty and properly; all the larger ones will also thus travel homeward and not be discharged onto the terminal with undesirable speed, but will land thereon so gently that a player can conveniently and safely grasp one as it emerges from beneath the overhanging part of the loop, and so that, 5 if not thus taken off by the player, it will roll on toward the terminal stop and against any ball or balls already congregated on the ball-rack without the least undue concussion.

10 To enable those skilled in the art to which my invention relates to make and use a returnway comprising my invention, I will now proceed to describe the novel construction I have devised, referring by letters to 15 the accompanying drawings forming part of this specification, and in which I have shown my said invention carried out in that precise form of "loop-the-loop" returnway in which I have, so far, successfully practised it.

In the drawings, Figure 1 is a side elevation, on a scale of about one-sixteenth full size, of my improved returnway—with a part broken out and the end portions moved 20 closer together, to shorten the space occupied. Fig. 2 is a partial top view of the pit-end portion and part of the low-down part only of the same, on the same scale. Fig. 3 is a detail view, on a scale of about 25 one-quarter full size, of the receiving end portion of the ball-rack or "terminal." Fig. 4 is a partial side view of the "loop" or players' end portion only of the return, drawn on a scale of about one-quarter full 30 size. Fig. 5 is a vertical sectional view taken in a plane indicated by the dotted line π at Fig. 4. Figs. 6, 7, 8, 9, 10 and 11 are diagrammatical cross-sectional views of the ball-track, or track-rails, drawn about full 35 size, to illustrate particularly what I will hereinafter explain with reference to the bearing surfaces on these rails of the largest three balls (used in playing ten-pins), and of the smallest three balls used in the games 40 of "duck-pins" and "candle-pins."

Wherever a given part appears in more than one of these figures, it will be found everywhere designated by the same letter or figure of reference.

45 In the drawings, A is the transverse portion of the ball-track that is located, as usual, above the back side of the pit and onto which the bowled balls are put, by the "pit-man" to roll home to the players for reuse; while A¹ is the quadrant or curved part by which the direction of travel of the balls is translated to one in alinement with the sweep A³ onto which they pass, rolling first, however, from the said quadrant A¹ 50 onto the upper end of the said sweep, over

the straight and slightly oblique portion A² of the track.

The sweep, which is of about the profile (in side view) shown, merges at its lower end into the "low-down" horizontal portion A⁴ of the returnway, located about as usual; and all these parts of the return are properly supported at h, i, j and j¹ by any desirable means, in about the usual manner.

The horizontal portion A⁴ of the ball-track merges at the player's end of the alley, as shown, and in about the usual manner of the present "loop-the-loop" returns, into the lower part of the "loop" L which, as usual, is curved backward, upwardly and forwardly, as seen, and after the fashion of this part of the present "loop-the-loop" returns, and so that its uppermost portion overhangs the rearmost, ball-receiving, end of the "terminal" B, C; but this "loop" 85 portion B, C, is made and arranged relatively to, or is combined with the rearmost end of the "terminal" in a materially different and novel manner, to conduce to the novel mode of operation of my improved returnway, in which the new results attained 90 to flow from these two novel structural features, viz: 1st, the novel cross-sectional shape of the ball-track, on which the balls travel by inertia all the way from the pit-end to the discharge end of the said ball track on which they roll; and 2nd, the novel combined arrangement together of the overhanging part of the "loop" and the overhung, rearmost, ball-receiving portion of the 95 "terminal" or ball-rack. And these novel structural features I will now specifically explain by reference to the drawings.

By an inspection of the full size cross-sectional views 6 to 11 inclusive, showing 105 the peculiar and exact shape of the ball-track (of the two similar rails composing it) it will be observed that the smallest ball d—shown at Fig. 6—in rolling home contacts with the rails L only at the points 4, 110 4; or, in other words, rolls on a bearing surface which, relatively to the circumference of the ball is practically a mere line of contact; while, as shown at Fig. 7, the next larger ball e—the 4½ inch—rolls on the same ball track L in contact with surfaces the widths of which are equal to the spaces I have indicated on each rail by the pointers 5 and 6.

The object and effect of this peculiarity 120 of the track-rails is that the smallest ball d which, by reason of its light weight would not otherwise roll home fast enough to mount within the "loop" L will travel up within the loop with sufficient inertia to insure its landing on the terminal, as I have illustrated 125 its motion or travel at Fig. 1 where this ball d has rolled in contact with the loop rail far enough to insure its descent, in about the manner indicated in this figure onto the 130

terminal, where I have shown it landed. From which landing point it will gravitate or roll along on the "terminal" by reason of the usual slight obliquity of the latter.

5 An inspection of Fig. 7 shows that the next larger ball *e* rolls in contact with the same shaped rails on surfaces measured widthwise by the pointers 5, 6 at said figure, or on surfaces each of which is approximately $\frac{3}{8}$ ths of an inch wide. And this extent of bearing surfaces of the ball *e* on the rails operates, by reason of the friction encountered in rolling, to make this ball travel somewhat slower than it otherwise would by reason of its greater weight, and at a rate of speed in rolling up within the "loop" as indicated at Fig. 1, that will insure its landing on the terminal a little in advance (perhaps a couple of inches) of 10 the point at which ball *d* descends on the terminal, but in a proper desirable manner.

Referring now to Fig. 8, it will be seen that the 5-inch ball *f* there diagrammatically indicated, rolls in contact with these 15 same track-rails on spaces at either side measured by the distance between the pointers 7 and 8 on each side of said figure; so that the surfaces with which the circumference of this ball frictionally contacts on the 20 two rails measure, respectively, widthwise approximately $\frac{3}{8}$ ths of an inch, so that this largest and heaviest ball of the three smaller ones will roll home slower than it otherwise would; and also so that, keeping in contact 25 longer with the overhanging part of the loop, will leave the latter and descend onto the terminal at a point 2 or 3 inches in advance of that at which ball *e* landed.

The three shown balls of the larger sizes, 30 for playing ten-pins, seen at *a*, *b*, *c*, Fig. 1, in rolling home from the pit end of the returnway onto the "terminal" coact with the track-rails *L* as I will now explain by reference specially to Figs. 9, 10 and 11.

35 At Fig. 9 it will be seen that the 25-inch ball *a* contacts with the track-rails on spaces widthwise of the latter measured respectively by the distance between the pointers 9 and 10, at either side of this figure.

It will be observed that this measure of the frictional contact surface here is approximately $1\frac{1}{2}$ inches; because this much heavier ball needs to have its rolling speed or motion very materially checked, which is 40 done by having the much greater contacting surface shown and by also having this surface extend farther up on the ball, so to speak, or nearer to its horizontal diameter, at each side.

45 At Fig. 10, it will be seen that the larger, 26, inch ball *b*, contacts, at either side, with the track-rail for a distance measured from 11 to 12; but this contact space being higher up so to speak, on the ball, the latter tends 50 to roll home slower.

At Fig. 11 it will be seen that the biggest ball of all,—the 27 inch ball *c*—contacts only from 13 to 14; but a greater tendency to slow down this ball exists by reason of the lines, or spaces of contact with the rails 70 being located higher up, so to speak, on the sides of the ball.

In practice I have found the structure shown to result in this 26-inch ball coming out from under the overhanging part of the 75 loop, onto the terminal at a rate of speed which enables a player to conveniently catch the ball with his hand, or hands, immediately or very soon after it lands on the terminal.

Of course, in order to permit the biggest ball *c* of all, to pass along between the overhanging part of the "loop" and the receiving portions of the terminal rails beneath it, the distance between the said overhanging 80 "loop" portion and the said portion of the terminal rails must not be at any point less than equal to the diameter of this biggest, "regulation" ten-pin ball *c*. And it is a material structural feature of my novel returnway that the space between the "contact line of ball *c*" of the loop and that of the terminal rails is exactly equal to the diameter of said biggest ball, and that these two contact lines are perfectly parallel, so that 85 after the ball *c* gets up onto the receiving ends of said terminal rails it will roll or travel thence all the way until it escapes or emerges from beneath the "loop," in frictional contact with the latter. This operates 90 to put a brake, so to speak, on the moving ball which (being pretty heavy) comes up very fast, and causes it to pass out from beneath the overhanging part of the "loop" 95 at so moderate a rate of speed that it can be 100 grasped or taken up by the player without danger of getting his hand hurt; and, so that if not caught up by the player it will not pass along on the terminal so fast as to effect any undue concussion with what balls 105 may be congregated on the latter.

This gaged distance between the said "contact" lines, and their parallelism, to induce to the mode of operation, I have explained is an essential feature of my invention.

While as shown at Fig. 11, the contacting rail surfaces (from 13 to 14) at each side of this biggest ball *c*, are not nearly so extensive (being only about $\frac{3}{4}$ ths of an inch) as 110 those of the lighter ball *a*, they are, it will be seen at Fig. 11, located higher up on the lower half of the ball's circumference, which tends to make the ball roll home a little slower, its speed being, however, still further checked in passing along between the loop and the terminal; while this peculiar construction enables me to get the much greater rail-bearing surfaces for ball *a* (to 115 slow down its speed) which, being much 120

smaller than c cannot receive any brake action from the overhanging portion of the "loop."

It will be seen from all I have set forth, 5 as to my improved construction of "loop-the-loop" returnway, that the operativeness of the same depends upon the ratios of the radii of the different sized balls to the perpendicular distances between the centers of 10 said balls and the horizontal planes that pass through the bearing or contact surfaces of said balls on the track rails; as I have clearly illustrated and described.

It will now be understood that the two 15 essential features of my invention reside in—1st, the peculiar shown and described profile, so to speak, in cross-section of the track-rails; and 2nd, the peculiar shown and described parallelism, and distance apart of 20 the contact lines or surfaces of the biggest ball on the overhanging part of the loop and the ball-receiving portions of the terminal rails. And, as experiment and actual practice have demonstrated, it is by reason 25 of these structural peculiarities that, in the use of my improved "loop-the-loop" returnway, all the balls (from the 27-inch circumference down to the 4-inch diameter) ever used on a bowling alley, for playing on the 30 same every sort of game, are properly homed.

By preference I provide the ball-receiving portions of the two terminal rails B, C, with an inlaid cushioning device m (see Fig. 3 35 at which alone I have illustrated the device) which in practice I have found efficient and desirable to lessen the slight concussive actions, shocks, to the smaller series of balls, as they necessarily descend out of 40 contact with the overhanging portion of the loop and land on the ball-receiving portion of the terminal—as illustrated with reference to the little ball d , by the dotted line at Fig. 1.

45 Having now so fully set forth the construction and mode of operation of my improved returnway, that those skilled in the art can make and use "loop-the-loop" returns embodying my invention, what I claim

as new and desire to secure by Letters Pat- 50 ent is:—

1. In a ball returnway, a track the rails of which are so shaped in cross-section that the ratio of the radius of any larger ball to the perpendicular distance between the center and the horizontal plane passing through the bearing surfaces of such ball is enough greater than the ratio of corresponding dimensions of any smaller ball to reduce to a desired extent the speed of return of such 60 larger ball relative to that of the smaller ball.

2. In a "loop-the-loop" genus of ball returnway, a ball receiving portion of the terminal and a portion of the loop overhanging the same, the ball contacting surfaces of each of which parts are parallel and the distance between which parts is just equal to the diameter of the biggest ("regulation") ball used on an alley. 70

3. In a ball returnway for bowling alleys, a track structure having an inner track and an outer track, each of uniform cross section throughout its entire length, said inner track being located immediately below the 75 level of the other track and close thereto.

4. In a ball returnway for bowling alleys, a track structure having an upwardly and backwardly curved terminal end, and a rack at said terminal end, located beneath 80 the top of said curved end, said track structure being of constant cross section throughout its length, and having an outer track and an inner track there between, the outer one being slightly above the inner, and the members of both tracks, spaced apart in such manner as to support all sized bowling balls at points near their largest diameters whereby their speed on the track is not appreciably lessened in traveling from one end to 90 the other thereof. 85

In witness whereof I have hereunto set my hand this 7th day of September, 1911.

J. N. McINTIRE.

In presence of—

F. DIEHL,
H. CROCHERON.
